UNITED STATES PATENT OFFICE.

TYCKO L. MATTSON, OF PASWEGIN, SASKATCHEWAN, CANADA.

CUFF-BUTTON HOLDER.

1,360,129.

Specification of Letters Patent. Patented Nov. 23, 1920.

Application filed March 26, 1918. Serial No. 224,863.

To all whom it may concern:

Be it known that I, TYCKO L. MATTSON, a citizen of Canada, residing at Paswegin, in the Province of Saskatchewan and Dominion of Canada, have invented new and useful Improvements in Cuff-Button Holders, of which the following is a specification.

The object of the invention is to provide a safety clasp or holder for cuff buttons as, for example, of the link type, to provide against loss of a button in the event that one end or head thereof should become disengaged from the button hole at one side of the cuff, and in this connection to provide a device of this type which may be readily attached and detached, and which when attached remains in engagement by inherent spring action.

Further objects and advantages of the invention will appear in the course of the following description, it being understood that changes in form, proportion and details of construction may be resorted to, within the scope of the appended claims, without departing from the spirit of the invention.

In the drawings:

Figure 1 is an end view of a cuff showing a button of ordinary type engaged therewith, the safety clasp, illustrating one embodiment of the invention, being shown applied thereto in the operative position.

Fig. 2 is a plan view of the clasp.

Fig. 3 is a similar view showing the terminal lobes or rings collapsed by terminal pressure, as by the thumb and finger of the operator's hand, to spread or separate the jaws, located intermediately of the lobes or rings, for engagement with the shank of a cuff button.

In the illustrated form of the invention, it will be a matter of convenience to refer to the same as in the general shape of a figure eight or 8-shaped, the same preferably being constructed of a single strip of wire or the equivalent thereof, and also being of a spring material so as to yieldingly maintain the general form indicated and resume such form after having been distorted as by terminal pressure to collapse the lobes or rings 10 and 11, in the act of applying the device

to, or removing the same from, the shank of a button which in Fig. 1 is illustrated at 12 in the normal or usual engagement with button holes in the cuff 13.

The corresponding sides 10^a and 11^a and 10^b and 11^b are extended beyond the point of intersection of the sides of each lobe or ring, and are bowed in opposite directions to form inwardly facing concaved or looped jaws 14 and 15 respectively. These jaws are designed to clasp the shank of the button snugly when the lobes or rings are in their normal position or unrestrained, and yet by pressing upon the extremities of the clasp in the directions indicated by the darts in Fig. 3 the lobes or rings are collapsed or distorted to cause a separation of the jaws which permits of their engagement with the shank of the cuff button, at the inner surface of the cuff, after one button head, as for example the smaller one, has been inserted through the button hole in one side of the cuff.

Obviously in the event that the smaller head of the cuff button should become disengaged from the other side of the cuff, the clasp, being resiliently held in engagement with the shank, will prevent the loss of the button.

What is claimed is:

1. A safety clasp for cuff buttons, of substantially the form of a figure eight with the corresponding sides of the lobes or rings thereof extended beyond the intersection and looped to produce facing concaved jaws. 80

2. A safety clasp for cuff buttons, consisting of a substantially 8-shaped spring strip or wire and provided between the lobes or rings thereof with separable facing jaws carried respectively by the corresponding sides of said lobes or rings. 85

3. A safety clasp for cuff buttons, consisting of a substantially 8-shaped spring strip of wire comprising inherently expansible lobes or rings, the corresponding sides of which are extended beyond the intersection to form facing jaws, separable by the forcible compression of the lobes or rings. 95

In testimony whereof I affix my signature.
TYCKO L. MATTSON.
